(57) **CLAIM**

The ornamental design for a carry handle, as shown and described.

DESCRIPTION

FIG. 1 is a frontal, rightward, downward perspective view of the carry handle according to our design;

FIG. 2 is an enlarged frontal, rightward, downward view thereof;

FIG. 3 is a top plan view thereof;

FIG. 4 is a frontal elevational view thereof;

FIG. 5 is a rearward elevational view thereof;

FIG. 6 is a right elevational view thereof; and,

FIG. 7 is a left elevational view thereof.

The broken line showing of the suitcase in FIG. 1 is included for the purpose of illustrating portions of environment of the carry handle and forms no part of the claimed design.
